UNITED STATES PATENT OFFICE

1,963,292

METHOD OF AND APPARATUS FOR PRE-SHRINKING AND CONDITIONING FABRICS

Adolph Walter Buhmann, New York, N. Y., assignor to A. W. Buhmann, Inc., New York, N. Y., a corporation of New York

Application May 1, 1931, Serial No. 534,394

3 Claims. (Cl. 26—48)

My invention relates to a method of and apparatus for pre-shrinking and conditioning fabrics. Fabrics made of synthetic fiber, such as rayon, have certain objectionable characteristics such as a peculiar tint, a rough or harsh feel, and an undesirable sheen, which must be removed by special treatments to make the fabric suitable for most purposes.

In my Patent, No. 1,786,421, I have disclosed a method of and apparatus for conditioning fabrics of synthetic fiber and while the method therein disclosed has proven to be sufficient for many classes of fabrics made from synthetic fiber to make them suitable for the manufacture of wearing apparel; there are certain types of such fabrics such as rayon linings, which require additional treatment. In my said patent the fabric is permeated with steam at a pressure of approximately 15 pounds per square inch and a temperature of approximately 213° F., and thereafter cooled by withdrawing the steam and forcing air through the fabric. The patent shows the fabric as being blanketed during the treatment.

An important object of my present invention is to provide a method of conditioning and treating fabrics, particularly fabrics of synthetic fiber, to remove therefrom the objectionable characteristics and to impart thereto a soft texture and rich and natural appearance.

Another object of my present invention is the provision of a method of and apparatus for obtaining absolute pre-shrinkage of fabrics particularly those made of synthetic fiber.

Another object of the invention is the provision of apparatus for obtaining the above result without subjecting the goods to any tension during treatment, so that complete shrinkage is obtained.

To the accomplishment of the foregoing and other objects and advantages of the invention which will become apparent hereinafter, I provide means for progressively subjecting the fabric to the penetration of steam at a pressure of approximately 15 pounds per square inch and a temperature of approximately 213° F. to cause a preliminary contraction of the fibres; then subjecting the fabric to the action of dry heat to evaporate the moisture with which the fabric has been saturated, thus obtaining a thorough shrinkage in length and width, and then folding the fabric while simultaneously subjecting it to atmospheric action which further dries the fabric resulting in further shrinkage.

During the above process and the operation of the machinery for accomplishing the same,

the fabric is not subjected to any tension as will be more apparent after reading the following detail description of the invention as disclosed in the accompanying drawings wherein is shown a preferred embodiment of the invention and in which

Fig. 1 is a side diagrammatic view of a machine with parts in section;

Fig. 2 is a vertical sectional view through the steaming apparatus; and

Fig. 3 is a view taken on the line 3—3 of Fig. 1. Referring to the drawings, the numeral 5 designates a supporting frame at the top of which the perforate cylinder 6 is rotatably mounted on bearings 7, with sprocket wheels 8 and 9 mounted for rotation with the cylinder 6 at opposite ends thereof. A main drive shaft 10 is journaled in the frame and carries a gear wheel 11 and sprocket wheel 12, the shaft being driven from a source of power not shown.

A chain 13 is trained around the sprocket wheels 9 and 12 and across the tensioning roller 14 to rotate the cylinder 6, and a chain 15 is trained around the sprocket wheel 8 and the wheel 16 across the tensioning roller 17 so that as the cylinder 6 rotates it will rotate the wheel 16 for a purpose to be later described. The fabric 18 is passed over roller 19 and under roller 20 and between the expander 21 in the nature of a conical roller journaled in the frame in proximity to the outer periphery of the cylinder 6. The fabric passes over around the cylinder 6 covering an arc of approximately 250° as shown in Fig. 1 and from the cylinder it passes over an inclined heated table 22 and over the roller 23 at the lower end of the table on to the movable platform 24. The roller 23 is operated by the belt or sprocket chain 25 which is passed around the wheel 26 which is rigidly connected to the gear 26' in mesh with and driven by the gear 27 which in turn meshes with the gear wheel 11 on the main shaft 10. The ratio between the wheels 23, 26 and 11 is the same as the ratio between the wheels 9 and 12 so that the roller 23 will rotate at the same speed as the cylinder 6 in order that the fabric will be moved evenly and without any tension being exerted thereon.

The platform 24 is mounted on wheels 28 which preferably are on a track 28' and the platform is connected by a link 29 with the lever 30 fulcrumed at 31 to the frame. A connecting rod 32 is pivotally connected at 33 to the wheel 16 and at 34 to the lever 30 so that as the wheel 16 is rotated by the chain 15 and sprocket wheel 8 the crank shaft 32 will reciprocate to swing the lever

30 on its fulcrum to move the link 29 backwards and forwards at predetermined distances thereby reciprocating platform 24 beneath the roller 23 so that the fabric 18 will be folded thereon as shown in Fig. 1, it being apparent that as the platform 24 moves back and forth the stretch of fabric between the roller 23 and the platform is wafted in the atmosphere.

Within the cylinder 6 is mounted the baffle plate 35 which directs the steam from the jets 36 of a steam spray connected by pipe 37 with a source of supply not shown, through a segment of approximately 120° upwardly toward the fabric which is progressively passed over the cylinder in the manner hereinbefore described.

As has been mentioned the steam issuing from the jets is under approximately a pressure of 15 pounds per square inch and of a temperature of approximately 213.067° F.

20 The operation is as follows:—

The fabric to be pre-shrunk and conditioned is passed over and under guide rollers 19 and 20 respectively and between the expander 14 and cylinder 6 and around the cylinder 6 to a point 25 above and in proximity to the inclined heated table 22, then downwardly across the top face of the table and over the roller 23 on to the platform 24. As the fabric traverses the course just mentioned, the table 22 is heated and steam at 30 the temperature and pressure above mentioned, which affords a saturated steam, is issuing from the jets 36 and is being deflected by the baffle plate 35 through the openings 38 in the cylinder 6 over a substantial portion thereof so that a 35 single thickness or layer of fabric is continuously and successively subjected first to the action of the saturated steam as it passes over the roller 6 causing a contraction of the warp and filling threads naturally resulting in shrinking of the fabric, and the contraction of the threads is increased when the fabric is subjected to the action of the dry heat emanating from the table 22 which evaporates the moisture in the fabric as will be obvious. The fabric is further dried when 40 it is subjected to the atmosphere as it is wafted between the roller 23 and movable platform 24. At no time during the above process is the fabric subjected to tension which would prevent complete shrinking as it runs loosely and smoothly 45 over the cylinder 6, table 22 and roller 23 on to the platform 24 the movements of which are synchronized by a proper ratio between the parts of the mechanism which drive the cylinder 6, roller 23 and platform 24.

50 A fabric after being treated on the apparatus and in accordance with the process hereinabove disclosed, is completely shrunk. If a fabric of synthetic fiber treated in accordance with the foregoing disclosure is then subjected to the method disclosed in my Patent 1,786,421 the appearance and texture of the fabric is completely altered, in fact a totally unexpected result is obtained and a rayon fabric which has been pre-shrunk in accordance with the disclosure of this 55 application and then subjected to saturated steam while blanketed as disclosed in my said patent, will be found to possess a very soft and natural texture and a rich and natural appear-

ance and will be in proper and ideal condition for tailoring.

I believe that the apparatus and process disclosed herein possesses great utility in shrinking and conditioning all types of fabrics and I do not wish to limit the invention to the conditioning and pre-shrinking fabrics of synthetic fibers either on the apparatus itself or in connection with the methods disclosed in my said Patent No. 1,786,421, although a fabric of synthetic fiber which has been treated in accordance with the disclosure of this application and the method of my Patent No. 1,786,421 acquires a soft and comfortable feel which is totally lacking in fabrics of synthetic fiber treated by other means or processes which have up to the present time failed to impart to rayon fabrics the appearance, texture and natural characteristics long sought.

While I have not shown a mechanical connection between the apparatus herein disclosed and that disclosed in my said Patent No. 1,786,421 it should be obvious that the fabric which is fed on to the platform or over the roller 23 can be passed to apparatus such as disclosed in my said patent for treatment in accordance with the disclosure thereof.

I claim:

1. Apparatus for shrinking and conditioning fabrics comprising a perforate steaming cylinder, a heated surface adjacent the cylinder to receive the fabric therefrom, a roller at the end of said surface remote from said cylinder, and means for rotating said cylinder and roller without winding the fabric on either, said means being synchronized to continuously move the fabric over said cylinder, heated surface and roller without tension on the fabric.

2. Apparatus for shrinking and conditioning fabrics comprising a supporting frame, a perforate cylinder rotatably mounted thereon, a steam spray within the cylinder, a heated surface at one side of the cylinder, an expander rotatably mounted on the frame at the other side of the cylinder to guide the fabric against the surface of the cylinder, the heated surface at the other side of the cylinder being disposed to receive the fabric therefrom, a roller at the other end of said heated surface, and means for rotating said expander, cylinder and roller, said means being synchronized to continuously move the fabric over the cylinder, heated surface and roller without tension on the fabric.

3. In apparatus of the character described, a perforate cylinder, a roller remote from the cylinder and in alignment therewith, said cylinder and roller being adapted to receive a strip of fabric on arcs of their surfaces without winding the fabric thereon, means for saturating the portions of the fabric on the cylinder with steam to moisten said portions, means intermediate said cylinder and roller to dry the moistened portions, and means for rotating the cylinder and roller at similar speeds to progressively move the strip over said cylinder, drying means, and roller without tension on the fabric from the time it is moistened until it has passed over the rollers.

ADOLPH WALTER BUHLMANN.
